[57] CLAIM

The ornamental design for a skate blade assembly, as shown.

DESCRIPTION

FIG. 1 is a perspective view of the skate blade assembly;

1 Claim, 6 Drawing Sheets

FIG. 2 is a side elevation view of the skate blade assembly;
FIG. 3 is the opposite side elevation view of the skate blade assembly as shown in FIG. 2;

FIG. 4 is a top plan view of the skate blade assembly;
FIG. 5 is a bottom plan view of the skate blade assembly;
FIG. 6 is a front elevation view of the skate blade assembly;
FIG. 7 is a rear elevation view of the skate blade assembly;
FIG. 8 is a cross sectional view along cut line 8—8 of FIG. 2;

FIG. 9 is a perspective side view of a modified embodiment of the design shown in FIGS. 1-8;

FIG. 10 is a side elevational view thereof;

FIG. 11 is the opposite side elevational view thereof;

FIG. 12 is a top plan view thereof;

FIG. 13 is a bottom plan view thereof;

FIG. 14 is a front elevational view thereof;

FIG. 15 is a rear elevational view thereof;

FIG. 16 is a cross sectional view along cut line 16—16 of FIG. 10;

FIG. 17 is perspective side view of a second modified embodiment of the design shown in FIGS. 1-8;

FIG. 18 is a side elevational view thereof;

FIG. 19 is the opposite side elevational view thereof;

FIG. 20 is a top plan view thereof;

FIG. 21 is a bottom plan view thereof;

FIG. 22 is a front elevational view thereof;

FIG. 23 is a rear elevational view thereof; and,

FIG. 24 is a cross sectional view along cut line 24—24 of FIG. 18.
